DISPLAY DEVICE

Erwin Wagner, Chicago, Ill., assignor to Wagner Sign Service Incorporated, Chicago, Ill., a corporation of Illinois

Application January 10, 1938, Serial No. 184,141

5 Claims. (Cl. 40—140)

This invention relates to display devices, and is particularly concerned with improvements in illuminated display signs of the general character disclosed in the co-pending application, 5 Ser. No. 130,507, filed March 12, 1937.

The co-pending application discloses a sign structure comprising a container or box having a display opening which is closed by a translucent panel, for example, a glass panel. The glass 10 panel is mounted in a holder or carrier which comprises two channel members attached at opposite sides to its edges and connected by cross members extending across the surface of the panel and spaced somewhat from it. These cross 15 members are provided for holding removable signs or characters. The holder or carrier protects the panel, facilitates the mounting thereof, and provides numerous other advantages, all as pointed out in detail in the co-pending application.

20 The present invention constitutes an improvement on such a structure. It provides a carrier or holder for the glass panel which embraces all sides of the panel, thus protecting all its edges. This new holder or carrier may be adapted for 25 use with existing signs, but is particularly intended for use with a sign which also has an improved box or container frame. In the old boxes for such illuminated signs it was necessary to provide a frontal channel running circumferentially along the display opening for receiving the glass panel with or without such a holder or carrier as described in the co-pending application. The structure disclosed herein is adapted for use 30 with a box having a display opening which is merely defined by a circumferential edge or ledge. The panel or panel sections of the new structure may be attached to this ledge by virtue of H 35 channel members which constitute part of the new panel carrier.

40 Some of the advantages gained by this new structure are: The structure of the display box itself may be made simpler and accordingly cheaper. The glass panel is better protected than heretofore, and the steps of inserting it are greatly facilitated. The work of mounting is rendered safer than in previously known structures.

45 The above noted advantages and other objects and features of the invention not yet particularly mentioned will be brought out in the detailed description rendered below with reference to the accompanying drawing, in which:

50 Fig. 1 is a partial plan view of one form of a sign made according to the invention, with parts

broken away and in section so as to illustrate details;

Fig. 2 illustrates a section of the structure taken along line 2—2 of Fig. 1;

Fig. 3 represents, on an enlarged scale, an assembly of a panel section with its new carrier;

Fig. 4 is a partial view of a modification; and

Fig. 5 shows another modification in the same manner as the one shown in Fig. 4.

Some of the details in the drawing are shown 10 on an enlarged and distorted scale relative to other parts so as to support the understanding of the invention.

Referring now to the drawing, wherein like parts are identified by like reference numerals, 15 Fig. 1 indicates generally the box of such a display sign having a rear wall 12 (Fig. 2) and frontal openings 13 and 14. These two frontal openings are separated interiorly by a cross plate 15 (Fig. 2) which carries a strip-like member 16. 20 The upper frontal opening 13, as shown in Fig. 1, is thus exteriorly defined at the upper side of the sign by the ledge 17 and at the bottom by the member 16 forming a corresponding ledge. Another ledge is indicated on the left side at 18, 25 and of course a corresponding ledge is provided on the opposite right side of the sign. The frontal opening 13 is thus defined circumferentially by a continuous edge or ledge. The bottom of the cross strip 16 would define the upper ledge 30 of the next lower frontal opening 14, and the continuation 19 of the ledge 18 would constitute the left end of the opening 14. The sign may have a number of superimposed frontal openings, such as 13 and 14, or only one display opening, 35 each having such a frontal edge or ledge. As compared with previous structures, this is an advantage because previously it was necessary to provide a circumferential frontal channel which served as a holder or receptacle for the glass 40 panel and any holder structure for it, as disclosed, for example, in the previously noted co-pending application.

Inside of the box or in each compartment thereof may be suitable provisions for supporting illuminating means, such as the members 20 and 21 carrying lamps, such as 22, 23 and 24. These supports may, of course, assume a different shape, if desired.

The glass display panel may be in sections, or 50 it may be in one piece. It is in either case provided with a holder or carrier such as indicated in Fig. 3. It is assumed in Fig. 1 that sectional glass panels are used, and the particular section shown in Fig. 3 on an enlarged scale is the second 55

section, also indicated in Fig. 1 at 25. The carrier and holder for this glass panel is shown, not only on an enlarged scale, but parts of it are also on a distorted scale, in order to bring out the 5 details more clearly. It comprises an upper and a lower channel member which is H-shaped in cross section, as indicated at 26 and 27, respectively. These channel members are in reality much smaller, as compared with other portions. 10 The upper forked end of the holder member 26 is longer than its corresponding lower forked end which attaches to the upper edge of the glass panel 25. Conversely, the upper forked end of the member 27, which engages the lower edge of 15 the glass panel 25, is longer than its lower forked end. The reason for this will be presently explained. These H-shaped channel members 26 and 27 are in this embodiment held together by strips 28-29 which may be welded at their ends 20 to the H members at points 30, 31, 32 and 33. Such strips as 28 and 29 may be only provided at the front side or in back of the panel, or there may be a pair of such strips at either end of the panel, the latter structure being indicated in Fig. 25 3 at the right side thereof, showing a strip 29 at the front and a companion strip 34 on the other side of the glass panel 25. The glass panel is thus marginally completely enclosed by its frame or carrier. Cross members, such as 35 and 36, 30 may be attached to the connecting strips 28 and 29 in any suitable manner. They may be welded to these strips or, in lieu of welding, they may be made removable with reference to the carrier strips 28 and 29 in a manner such as disclosed in 35 the previously mentioned co-pending application. The letters or characters which are to be displayed in the front of the glass panel may be attached to these cross members 35-36.

Referring again to Fig. 1, the glass panel 25 40 with its carrier, comprising the members 26, 27, 28 and 29 and the cross members 35-36, is shown in place. Another panel 25', having an identical holder or carrier with its individual portions marked in corresponding primed reference numerals, is shown in place in the sign at the left of the panel 25. Other similarly constructed panels may be attached alongside and adjacent the panel 25 so as to cover up the display opening 13. Each panel is inserted in place by first 45 taking the panel with its carrier and lifting it with reference to the display opening of the sign so that the corresponding ledge, such as the ledge 17, first enters the long upper forked end of the H-shaped carrier member 26, thus lifting the 50 panel and its carrier, and particularly its lower H-shaped carrier member 27 over the bottom ledge 16 of the display opening, whereupon the panel and its carrier may be dropped into place into the position shown in Figs. 1 and 2, with the 55 bottom ledge 16 entered into the lower forked end of the H member 27. The channel members, such as 26-27, and also the corresponding channel members shown in other embodiments, may be of different width, if desired, or they may be 60 made from the same stock and may accordingly be of the same width. As already remarked previously, these H members are shown on a larger scale than other portions of the structure in order to clearly indicate their shape. A sign of 65 this type, as shown in Fig. 1, may be quite large, several feet high and of considerable length and depth. The ledges or edges, such as 16, 17, 18, 19, would, of course, be considerably larger in an actual installation than the H members of the 70 carriers.

After the display opening of the sign is thus closed with the single panel or with a panel comprising sections, such as described, fully in place, the cross members 35-36, 35'-36' and the corresponding cross members of the additional 5 panels, will form substantially continuous cross members or bars for supporting letters or characters forming a desired message. For the sake of convenience, we have indicated a message which may be displayed on the sign, consisting of 10 figures and letters and forming, for example, the message "3 IN 1". Each of the characters or letters such as 40 (numeral 1 in Fig. 1) may be provided with peripheral flanges having inclined notches for engagement with these cross members, but these letters may also be of a different structure, as indicated, for example, in the co-pending application; e.g., the cross members may be channel-shaped so as to accommodate characters or letters having top and bottom lugs or the 15 like.

In the embodiment thus far described the carrier frame may be prefabricated and the glass panel may be inserted by sliding it sideways between the strips, such as 29-34, Fig. 3, and the 25 corresponding strips at the other side of the carrier, inserting it so that it is firmly held marginally by the carrier, as indicated. Channel-shaped connecting strips may be used, if desired, in lieu of the strips, such as 28-29. Such a structure is 30 indicated in Fig. 4, wherein 41-42 indicate the upper and lower H-shaped carrier members, respectively, and 43 indicates a channel-shaped member closing the corresponding end of the panel carrier. The panel itself is indicated in this 35 case at 44. Only the right end of a panel section and its carrier is shown in this figure. The corresponding left end may, of course, be of similar structure. The disadvantage of this particular embodiment resides in the necessity of doing as- 40 sembly work after inserting the glass panel into the carrier. The cross members for receiving the sign characters are omitted in this figure.

Another embodiment is shown in Fig. 5, where- 45 in the lower H-shaped carrier member 45 is shown detachable. The upper H-shaped carrier member 46 is provided at either end with a de- 50 pending connecting member 47 which may be either a channel member, such as indicated in Fig. 4, or there may be two oppositely located 55 strips each welded at its upper end to the H- shaped member 46. In either case the lower end of the member or members 47 is provided with extensions such as shown at 48-49, which project from the plane of the drawing and de- 60 pend downwardly, accommodating the H- shaped member 45 at the end thereof. Each of these ears or extensions may then be attached to the H-shaped member 45 by a threaded con- 65 nection such as 50, or may be secured in any 60 other suitable manner. The panel in this par- 70 ticular embodiment is indicated at 51. The car- 75 rier frame, according to the embodiment shown in Fig. 5, may be completely prefabricated, one pre-assembled portion consisting of the H mem- 80 ber 46 with its depending members 47, or their equivalent, one at either end thereof. The panel 51 is then inserted, and the H member 45 is put in place, embracing the lower edge of panel 51 and closing the entire assembly. The assembly 70 is completed by putting screws, such as 50, in place so as to attach the extensions 48 and 49 firmly to the ends of the H member 45. If de- 75 sired, the connecting members, such as 47, may be removable with respect to the upper as well 75

as to the lower H channel. It is merely necessary to provide for a connection, such as shown in Fig. 5, at either end of such connecting member.

5 Changes may be made within the scope and spirit of the appended claims, wherein I have defined what is considered new and desired to have protected by Letters Patent of the United States.

10 What is claimed is:

1. In a display sign, a display panel, a carrier therefor which comprises an upper and a lower channel member H-shaped in cross section, carrier means for connecting said channel members marginally of said panel, cross members connecting said carrier means, and character means removably attached to said cross members.

20 2. In a display sign, the combination of a glass panel with a carrier, comprising channel members marginally attached to said glass panel, two of said channel members being H-shaped in cross section and disposed opposite each other, and cross bars connecting the remaining channel members and disposed in parallel with said H-shaped channel members.

25 3. A display sign, comprising a display opening defined by a substantially continuous circumferential edge, a glass panel for insertion into said opening, a carrier frame for said glass panel comprising channel members forking away from

said panel for engagement with part of said circumferential edge to support said panel in said display opening, cross members attached to said carrier frame and extending in spaced relation to the surface of said panel and substantially parallel thereto, and characters removably attached to said cross members for display against said panel.

5 4. In combination, a glass display panel, a carrier frame for said panel comprising a supporting channel member forking away from the panel and forming a channel substantially parallel with the edge thereof, cross members attached to said carrier frame, character means removably attached to said cross members for display against said panel, and mounting means 10 embraced by said supporting channel member.

15 5. In combination, a glass display panel, a carrier frame for said panel comprising a removable supporting channel member forking away from the panel and forming a channel substantially alongside the edge thereof, cross members secured on said carrier frame, character means removably attached to said cross members for display against said panel, and mounting means 20 25 for holding said panel and said frame thereof, said mounting means comprising an edged member entering said forked supporting channel member.

ERWIN WAGNER. 30
